United States Patent Office

Des. 213,189
Patented Jan. 14, 1969

213,189

CAMPER TOP

William A. Ritter and Edward J. Anderson, both of 535
4th St., San Fernando, Calif. 91340

Filed May 28, 1968, Ser. No. 12,114

Term of patent 3½ years

U.S. Cl. D14—27
Int. Cl. D12—10

FIG. 1

FIG. 2

FIG. 3

FIG. 4

FIG. 5

We claim:

The ornamental design for a camper top, substantially as shown and described.
